UNITED STATES PATENT OFFICE.

SIEGMUND CHIGER, OF BERLIN, GERMANY.

APPARATUS FOR SORTING AND TESTING COINS.

1,038,293.

Specification of Letters Patent. Patented Sept. 10, 1912.

Application filed December 18, 1911. Serial No. 666,574.

To all whom it may concern:

Be it known that I, SIEGMUND CHIGER, subject of the Emperor of Austria-Hungary, residing at 65 Kurfurstendamm, Berlin, Germany, have invented new and useful Improvements in Apparatus for Sorting and Testing Coins, of which the following is a specification.

This invention relates to a new or improved apparatus for sorting and testing coins and the object of the invention is to effect the sorting of the coins not only according to their diameter, but also according to their thickness, to avoid the blocking up of the openings by thicker coins to enable rapid sorting to be effected.

The invention consists in guiding the coins positively and successively over two tracks or ways which lie one above the other and of which, the one has openings of different widths corresponding to the diameters of the coins, while the other has openings of different heights corresponding to the thickness of the coins. The coins are conveyed into those openings which they fit, as will be hereinafter particularly described and ascertained.

A suitable construction of apparatus according to the present invention is illustrated in the accompanying drawings in which—

Figure 1 is a transverse section of the apparatus with certain parts omitted. Fig. 2 is principally a longitudinal section along the line A—A of Fig. 1, but shows certain parts in vertical section and elevation which are not seen in Fig. 1. Fig. 3 is a sectional plan of Fig. 2. Fig. 4 is a transverse section on the line IV—IV Fig. 2 and Fig. 5 shows a detail in plan.

The hopper 1 serves for the reception of the money or coins of any desired size and thickness. The bottom of this hopper is inclined and leads to a receptacle 2. Above the receptacle the hopper 1 has an opening 3, which can be closed and opened by means of a slide 4 which can be raised and lowered. The movement of the slide 4 is derived from cams 5 on a cam shaft through the aid of a spring-operated lever 6. The receptacle 2, which receives the money which falls out of the hopper 1, has an opening 7.

Upon the bottom of the receptacle 2 is movably mounted a slide 8 which is pivotally connected to a pivoted lever 9 which is

operated by the cams 5 against the action of a spring and can be moved to and fro thereby, the slide 8 being carried with it. The slide serves to convey the lowermost coin lying in the receptacle 2, which it can thrust out of the receptacle, the coin passing on to a plate 10 which is provided with openings 11 and 12 (see Figs. 1 and 5.) The openings 11 and 12 are of different diameters, the opening 12 being greater than the opening 11, so that the coins which have a greater diameter than the opening 11 can be conveyed onward over the opening 11 by means of the slide 8 into the opening 12 while those coins of which the diameter is the same as, or less than, the diameter of the opening 11 pass through the latter into a tube 13 or the like wherein they form a pile.

Upon the bottom of the receptacle 13 is movably mounted a flat slide 14, which is connected to a suitable device for reciprocating it. In the constructional example shown, this device consists of a lever 16 pivoted at 15 and adapted to be operated by cams 17 for example against the action of a spring 16a. The lever 16 is pivotally connected to the slide 14. The tube 13 has an opening 18 through which the coins are moved by means of the slide out of the receptacle and on to a plate 19, which is provided with extensions 20. These extensions 20 are reduced in steps at 21 and 22 so as to form shoulders and so that the distance of the two extensions from each other is increased by stages. To the extensions are attached leaf springs 23 between which the coins can be moved on to the extensions or ledges, the coins being guided at the side by the springs and always held central.

Above the ledges is fixed a plate 24, which has a central longitudinal slot 25, (see Fig. 4). Above the plate 24 and on rollers 26 is mounted an endless chain or band 27, which has fixed projections 28, which may be T-shaped as shown in Fig. 4, at certain distances apart, and when the band is moved in the direction of the arrow these projections pass along the slot 25 so that their ends beneath the plate 24 strike against the coins lying on the plate 19 and the ledges 20 and are thus enabled to convey them onward along the ledges 20 and between the springs 23 in the direction of the arrow as long as the coins are supported by the ledges.

20. Upon the underside of the plate 24 are placed leaf springs 29, which tend to press the coins downward on to the ledges 20 so that a coin which fits any graduated enlargement of the intermediate space between the ledges 20 is pressed downward into the intermediate space, when it arrives over that enlargement by the pressure of the springs 29. The space between the ledges 20 is bounded below by a plate 30, which forms the bottom of the graduated recess. This plate 30 has a longitudinal slot 31 in it beneath which a conveyer band 32 or the like is moved in the direction of the arrow. This conveyer band is led over guide rollers 33 and over a driving pulley 34 and is provided with tappets 35 which are so arranged that they project through the slot 31 and into the space above the plate 30 as shown in Fig. 4.

In the space bounded on the sides by the ledges 20 and at one side thereof is fixed a blade spring 36. The lower edge of each of these springs 36 is placed a certain distance above the plate 30 as is shown in Fig. 4, so that a free space is left under the springs through which the right coin can pass, without coming into contact with the spring 36 and without being acted upon thereby. In the ledge opposite the spring 36 are provided recesses 37 and 38 of different heights but the diameters of which are equal to the distance apart of the ledges 20 at the places where the recesses are situated. The height of the recess 37 is somewhat greater than the distance of the upper edge of the spring 36 from the upper surface of the plate 30, and the height of the recess 38 is somewhat greater than the height of the recess 37. Instead of the spring 36 oblique cross bars 40 may also be arranged between the ribs 20. These cross bars are arranged at a fixed distance from the plate 30, so that a coin of inferior thickness can be conveyed through the space left between a cross bar and the plate 30 without striking against the bar, while coins of greater thickness than these strike against the cross bar and are conveyed by means of tappet 35 along the bar to a lateral opening 41 through which they are ejected. The coins pass through the openings 37, 38 and 41 into separate receptacles from which they are taken. In the plate 30 are made openings 42, which are intended for those coins which are conveyed by means of the tappet 35 on to the plate 30, without being deflected out of their path by the spring 36 or the cross bar 40.

60 The present invention enables a multiple sorting and testing of the coins to be carried out. The arrangement and formation of the ledges 20 allow the coins to be sorted according to their diameters, while with the aid of the spring 36, the cross bar 40 and the

lateral recesses 37, 38 and 41 in the ledges the coins can be sorted according to their thickness.

In front of the opening 7 of the receptacle 2 and in front of the opening 18 in the tube 13 is arranged in each case a spring 43 against which the lowermost coin can strike when advanced. Such coin lifts the spring and slides beneath it so that the lower end of the spring when free of the coin holds the next coin stationary. The object of this arrangement is to convey the coins singly through the opening, even when coins of different thicknesses are contained in the receptacle.

The improved apparatus may be employed partly or entirely in tills, automatic cash registers and similar apparatus. Instead of being used for money it may also be used for other checking purposes such as for sorting and counting checks and counters for example.

The apparatus may be driven by any suitable power medium or may be operated mechanically or electrically.

Claims.

1. In coin-sorting apparatus the combination of a track having a recess of different diameters at different portions thereof; and another track having openings of different heights with means for forcing the coins through the openings which they fit, substantially as described.

2. In coin-sorting apparatus of the character described, a track consisting of ledges, the distance separating the ledges being stepped to admit coins of different diameters between such ledges, and springs for guiding the coins centrally on the ledges, substantially as described.

3. In coin-sorting apparatus of the character described, a track consisting of ledges on which the coin is guided, there being openings of different heights in one of said ledges and a spring so arranged that the coins are forced into the opening through which their size permits them to pass, substantially as described.

4. In coin-sorting apparatus of the character described a track formed by ledges the distance separating such ledges being stepped so as to receive coins of varying diameter, there being openings of varying height in one of said ledges, blade springs for guiding the coins centrally on said ledges, and a blade spring for forcing the coins into the openings in one of said ledges, substantially as described.

5. In coin-sorting apparatus a track formed by ledges, transporting device for forcing the coins along the surface, and means for guiding the coins centrally on said track.

6. In coin-sorting apparatus of the character described, a track formed by ledges,

a transporting device for forcing coins along the track, blade springs for guiding said coin centrally on said track, one of said ledges having openings of varying height 5 to receive coins of different thickness, and means for forcing the coins into said openings; substantially as described.

7. In coin-sorting apparatus of the character described, a track having a recess of 10 different diameters at different portions along its length, there being openings in one side of said track, and means for guiding the coin through the openings which they fit; substantially as described.

15 8. In coin-sorting apparatus the combination of a track having openings of different diameters, means for positively moving the

coins along the said track, a second track arranged underneath the first track and adapted to receive the coins sorted by the 20 openings of the first track, means for positively moving the coins along the second track, there being openings of different height along the side of the second track, and means for pressing the coins toward 25 the last named openings.

In testimony whereof I have signed my name to this specification in the presence of two subscribing witnesses.

SIEGMUND CHIGER.
